CLAIM

The ornamental design for a air fryer, as shown and described.

DESCRIPTION

FIG. 1 is a perspective view showing an air fryer design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the air fryer shown in broken lines are included for the purpose of illustrating unclaimed portions of the air fryer and form no part of the claimed design.

1 Claim, 7 Drawing Sheets
